UNITED STATES PATENT OFFICE.

HENRY MEYERS, OF HYDE PARK, PENNSYLVANIA.

IMPROVED CONCRETE PAVEMENT.

Specification forming part of Letters Patent No. 42,589, dated May 3, 1864.

To all whom it may concern:

Be it known that I, HENRY MEYERS, of Hyde Park, in the county of Luzerne and State of Pennsylvania, have invented a new and Improved Concrete Pavement; and I do hereby declare that the following is a full, clear, and exact description of the same.

This invention relates to a composition which is particularly applicable to sidewalks, cellar-floors, &c., and is mixed together of sawdust, pulverized clay, coal-ashes, sand, and coal-tar, and spread on a foundation prepared of iron slag, cinders, coarse gravel, or other indestructible material cemented together by coal-tar.

To enable others skilled in the art to make and use my invention, I will proceed to describe it.

In putting down a pavement I first prepare the foundation, about three inches thick, of iron slag, cinders, coarse gravel, or some other suitable indestructible material, which is rendered solid by rolling with a heavy roller or by stamping. I then sprinkle it over with coal-tar, in order that the superincumbent composition may firmly unite with it.

The composition consists of sawdust, one part; pulverized clay, two parts; coal-ashes, two parts; sand, three parts. These ingre-

dients are intimately mixed with each other, and with a sufficient quantity of coal-tar to make a stiff mortar, and this mixture I spread on the foundation about two inches thick, more or less, and finally I add a light covering of my composition in a dry state—that is, without being mixed with coal-tar. Finally, I roll or stamp the whole until it is sufficiently hard.

This composition, when properly prepared and applied, as above described, produces a pavement which is very durable and quite impervious to water. It is peculiarly applicable to sidewalks, cellar-floors, and to such places in general where a dry hard floor or covering is desired. It can be made cheap and with comparatively little labor, and it resists all changes of the weather.

What I claim as my invention, and desire to secure by Letters Patent, is—

A concrete pavement composed of the ingredients above specified, and mixed together in about the proportion set forth, in combination with the foundation prepared as described.

HENRY MEYERS.
